UNITED STATES PATENT OFFICE.

WILLIAM F. PAGEL, OF SYCAMORE, ILLINOIS.

AIR PUMP.

Application filed November 25, 1921. Serial No. 517,430.

To all whom it may concern:

Be it known that I, WILLIAM F. PAGEL, a citizen of the United States, and resident of Sycamore, in the county of De Kalb and State of Illinois, have invented certain new and useful Improvements in an Air Pump, of which the following is a specification.

My invention relates to improvements in air pumps and has special reference to pumps for applying air pressure to plumbers' torches.

The object of my invention is to provide a pump piston of the leather cup kind in which the leather cup is constantly lubricated; in which the leather cup shall be expanded on the pressure stroke and shall be readily contractable on the suction stroke to the end of greatly increasing the efficiency, and facilitate the operation of such pumps.

A further feature of importance relates to the provision of an open chamber in the piston head for lubricant, which chamber is sealed or closed by the leather cup itself.

Further advantageous features of construction and operation will appear hereinafter.

My invention will be more readily understood by reference to the accompanying drawings forming part of this specification, and in which:

Figure 1 is a fragmentary side elevation of a plumbers' torch provided with an air pump made in accordance with my invention and shown in vertical section;

Figure 2 is an enlarged fragmentary central section of the lower end of the pump;

Figure 3 is a horizontal sectional view on the line 3-3 of Figure 2;

Figure 4 is a vertical sectional view similar to Figure 2 showing a slightly modified form of piston head;

Figure 5 is a horizontal sectional view on the line 5-5 of Figure 4; and

Figure 6 is a top plan view of another form of piston head.

In said drawings, 1 represents a plumbers' torch of the usual form adapted to supply fuel oil to the burner of the torch by air pressure. The torch is usually provided with an air pump mounted upon or attached to the reservoir of the torch for supplying the air pressure. I provide a pump 2 comprising a thin wall pump cylinder 3 mounted at its lower end in the outer end 4 of a bracket 5 which is attached rigidly to the torch reservoir and adjacent to the upper

end of the cylinder it is received and held in the outer end 6 of a rigid bracket 7. Within the cylinder 3 I provide a reciprocable piston 8 rigidly mounted on the lower end 60 of a piston rod 9 which projects through the upper end of the pump cylinder 3 and is provided on its upper end with a knob 10 for hand operation of the piston. The piston is of the leather cup kind and is provided with a leather cup 11 adapted to be secured in position on the piston rod between a metal washer 12 and a metallic piston head 13 in the usual manner. The piston head is threaded upon the lower end of 70 the piston rod and is adapted to clamp the washer 12 and the base of the leather cup 11 against the shouldered lower end of the piston rod. Instead of making the head 13 substantially completely filling the leather 75 cup according to the usual practice I provide a space between the upper part of the piston head within the cup as shown at 14, Figures 1 and 2, to permit the side wall 15 of the leather cup to readily contract on the 80 suction stroke and thus reduce friction between the piston and the cylinder. I also provide means such as vertical grooves or notches 16 to permit the air to readily enter into this space on the pressure stroke 85 of the piston and expand the cup against the cylinder wall thus preventing any escape of air past the piston on the pressure stroke. The air readily enters through the upper end of the cylinder around the piston 90 rod on the pressure stroke to follow the piston and as the cup readily contracts on the suction stroke the air easily passes the piston on this stroke.

I have found that in such air pumps, especially when used in connection with devices which make use of gasoline or similar fuels, that the leather cup soon dries up and becomes hard and usually must then be removed and replaced by a new cup. To 95 avoid this difficulty I provide the metallic piston head 13 with a chamber 16 preferably in the form of a circumferential groove between a central hub 17 and the open space 14 and when assembling the piston head, I pack this groove 16 full of vaseline or some similar lubricant. It will be seen that this chamber which is adapted to be filled with lubricant is sealed or closed by the base 18 of the leather cup and that consequently the cup is in constant contact with the lubricant and is adapted to be con-

tinuously lubricated thereby. In the form of piston head shown in Figures 2 and 3 I have produced the chamber 14 by making the piston head cone shape being smaller 5 at its upper end than at its lower end. The lower end 19 of the piston head substantially fills the mouth of the leather cup and I provide the outer edge or periphery of the piston head with the vertical grooves 10 or notches 16; before mentioned, to permit the entrance of the air on the pressure stroke into the circumferential space 14.

Instead of tapering the piston head as described I may make it with straight sides 15 as shown in Figures 4 and 5 providing a circumferential groove 20 at the outer corner of its upper surface and provide a plurality of longitudinal vertical grooves or notches 21 in its periphery to permit the 20 air to enter into the circumferential groove 20 and expand the leather cup on the pressure stroke.

Instead of providing a circumferential groove in the upper end of the piston head, 25 I may simply provide the periphery of the piston head with a plurality of vertically extending grooves or notches 22 as shown in Figure 6 providing sufficient of these grooves to permit the air to enter in between the upper end of the piston head and the bottom of the cup and effect the expansion of the cup in an obvious manner.

I preferably provide a compression spring 23 mounted loosely on the piston rod 35 above the piston head and adapted to cushion the piston at the upper limit of the suction stroke.

For delivering the compressed air from beneath the piston to the torch I provide a central port 24 in the bracket 4 which leads 40 into a valve chamber 25 in said bracket and I provide a horizontal passage 26 in the bracket connecting the valve chamber with the interior of the torch reservoir. The valve chamber 25 is closed at its lower end 45 by a screw plug 26 and within the chamber I provide a check valve 27 comprising a cork or similar yielding disk 28 mounted within a metallic head 29 which is carried 50 on a vertical stem 30. The outer wall 31 of the head 29 is formed over the outer edge of the cork disk to retain the disk in the head and I preferably provide a narrow valve seat 32 around the passage 24 against 55 which the cork disk is adapted to be yieldingly held by the pressure within the reservoir and by a compression spring 23 mounted on the stem 30 and adapted to push the valve 27 upwardly against the seat. The lower end of the stem 27 is

guided in a central guide opening 34 in the screw plug 26.

As the lower end of the metallic piston head is substantially flush with the lower edge of the wall of the leather cup, substantially all of the air is expelled from the cylinder on each pressure stroke. The only air remaining unexpelled being that in the short small passage 24 and consequently there is substantially no reaction from the pressure stroke but on the suction stroke a maximum quantity of air enters beneath the piston.

I have found with my improved piston that the piston remains in substantially perfect operating condition for many months and furthermore the pump is operated with a minimum of effort and at a maximum efficiency.

As many modifications of my invention will readily suggest themselves to one skilled in the art I do not limit or confine my invention to the specific details of construction herein shown and described.

I claim:

1. In an air pump, a cylinder, a piston in the cylinder, means for reciprocating the piston, the piston comprising a cup of leather or the like and a metallic head within the cup, the head provided in its inner end with an open chamber for lubricant, said chamber being sealed by the leather cup.

2. In an air pump, a cylinder, a piston reciprocable in the cylinder, the piston comprising a cup of leather or the like and a metallic piston head within the cup, the head tapered longitudinally being smaller at its inner end and substantially fitting within the cup at its outer end and provided with passages for permitting the air to enter between the piston and the cup on the pressure stroke, the small inner end of the piston provided with a circumferential groove adapted to be filled with lubricant such as vaseline, the groove being sealed by the base of the cup, as and for the purpose specified.

3. In a piston for an air pressure cylinder the piston comprising a leather cup and a metallic head within and substantially filling the cup, the head provided with an opening for receiving a material such as vaseline for keeping the leather soft, and the base of the leather cup sealing said opening as and for the purpose specified.

Signed at Sycamore, Illinois, this 10th day of November, 1921.

WILLIAM F. PAGEL.
